UNITED STATES PATENT OFFICE

SAMUEL B. CASSIDY, OF NEW YORK, N. Y.

DESIGN FOR A STORE FRONT

Application filed August 8, 1929. Serial No. 32,326. Term of patent 14 years.

To whom it may concern:

Be it known that I, SAMUEL B. CASSIDY, a citizen of the United States, residing at New York, New York, in the county of New York and State of New York, have invented a new, original, and ornamental Design for a Store Front, of which the following is a specification, reference being had to the accompanying drawing, forming part hereof.

I claim:

The ornamental design for a store front substantially as shown.

SAMUEL B. CASSIDY.
